MASONRY WALL REINFORCING TRUSS

William G. Smith, Ringgold, Ga., assignor to Lox-All Sales Corporation, Chattanooga, Tenn., a corporation of Tennessee

Filed Oct. 12, 1962, Ser. No. 72,086

Term of patent 14 years

(Cl. D51—1)

FIG.1

FIG.2

FIG.3

FIG.4

FIG. 1 is a top view of a first form of the invention including a pair of longitudinally extending members incorporating the new design, these members being interconnected by connecting means arranged in a continuous zig-zag fashion between the members;

FIG. 2 is a top view of a second form of the invention incorporating members identical to those shown in FIG. 1, these rods being interconnected by a plurality of equally spaced connecting means disposed perpendicular to the members;

FIG. 3 is an enlarged top view, of a portion of one of the longitudinally extending members which comprise the dominant feature of my design, the bottom being a mirror image of the top shown; and

FIG. 4 is an enlarged front view of the portion shown in FIG. 3, the rear view being a mirror image thereof.

In FIGS 1 and 2, portions of the truss are broken away to indicate indeterminate length.

The dominant features of my design reside in the portions shown in full lines.

I claim:

The ornamental design for a masonry wall reinforcing truss, as shown and described.
